COMBINED CAN OPENER AND BOTTLE CAP REMOVER

Lawrence M. Furey, Warwick, Va.

Application February 20, 1957, Serial No. 44,924

Term of patent 14 years

(Cl. D44—29)

(Granted under Title 35, U. S. Code (1952), sec. 266)

Figure 1 is a top perspective view of a combined can opener and bottle cap remover showing my new design; Figure 2 is a bottom perspective view;

Figure 3 is an end view thereof; and

Figure 4 is a fragmentary top plan view.

The dominant features of my design reside in the portions shown in full lines on the drawing.

The invention described herein may be manufactured and used by or for the Government for governmental purposes without the payment to me of any royalty thereon.

I claim:

The ornamental design for a combined can opener and bottle cap remover, substantially as shown and described.
